Parrot Drones. dated 2015. found online Nov. 12, 2015. <http://www.parrot.com/usa/gallery/bebop-drone/>.*Primary Examiner — Robert M Spear*Assistant Examiner* — Marissa J Cash(74) *Attorney, Agent, or Firm* — Marshall, Gerstein & Borun LLP(57) **CLAIM**

The ornamental design for a flying toy, as shown and described.

DESCRIPTION

FIG. 1 is a three-quarter front view of a flying toy that has the design.

FIG. 2 is a front view of the flying toy.

FIG. 3 is a rear view of the flying toy.

FIG. 4 is a left-side view of the flying toy.

FIG. 5 is a right-side view of the flying toy.

FIG. 6 is a top view of the flying toy; and,

FIG. 7 is a bottom view of the flying toy.

The broken lines represent elements of the flying toy that are not part of the claimed design, and form no part of the claimed design.
